UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

SEWING-MACHINE.

1,240,085.

Specification of Letters Patent. Patented Sept. 11, 1917.

Application filed October 9, 1913. Serial No. 794,279.

To all whom it may concern:

Be it known that I, LANSING ONDERDONK, a citizen of the United States, residing at New York, in the county of New York, 5 State of New York, have invented certain new and useful Improvements in Sewing-Machines, of which the following is a description, reference being had to the accompanying drawing and to the figures of reference marked thereon.

The present invention relates to new and useful improvements in sewing machines, and more especially to the construction of a sewing machine combined with a trimming 15 attachment which is a development of the "Deweese trimmer", illustrated in Patents Nos. 266,783 and 324,813, and in the patent to Durand, 698,912, granted April 29th, 1902. In these patents the fabric is severed 20 by toggle-trimming members, which are provided with crushing or abrading surfaces, coöperating one with the other to separate the material.

It has been found in practice, that when 25 an unusual thickness of material to be severed passes between the jaws, the gooseneck or overhanging arm will spring upwardly slightly, and the jaws being forced apart will snap back against each other, after the 30 thick place has passed. This has the effect of chipping out the abrading surfaces of the toggle and prevents their proper working. These toggles are simply brought together without unusual pressure upon them, 35 and thus ought to sever thick material as well as thin, but this has not worked out perfectly in practice.

The object of the invention, therefore, is, 40 first, to provide a novel construction of sewing machine frame for use in connection with such a trimmer, whereby the springing of the gooseneck or overhanging arm is prevented, and consequently the wear of the toggles much increased; and second, to provide a novel construction of the upper toggle-supporting mechanism.

The invention, therefore, consists in the means for carrying out the above objects, and in the matters hereinafter described 50 and referred to in the appended claims.

The invention is illustrated in the accompanying drawings, in which,—

Figure 1 is a side elevation of a sewing machine embodying my invention;

55

Fig. 2 is an end view of the machine;

Fig. 3 is a vertical section on the line 3—3 of Fig. 2.

Fig. 4 is a detail showing a portion of the trimming mechanism in front view, and the adjustable member on the throat plate, 60 which is laterally movable with the trimming mechanism;

Fig. 5 is a plan view of the work plate slide;

65

Fig. 6 is a side view of the same;

Fig. 7 is a sectional view through the work plate slide;

Fig. 8 is a detail in plan, showing a modified form of the throat plate; and

Fig. 9 is a side view of the same.

70

In these drawings, 1 represents the bed plate of the machine, and A the gooseneck or overhanging arm. To strengthen the gooseneck and prevent its springing, I cast the machine frame with a vertical web or 75 connecting piece B between the gooseneck and bed. It is understood that so far as this structure is concerned, it may be useful in other types of machines than those to which toggle trimmers are applied, although it is 80 of special value in such a machine, to prevent any springing of the gooseneck or overhanging arm.

The bed plate 1 of the sewing machine carries a bracket 2, on which is pivoted the 85 lower toggle 3 of the trimming members. The main shaft 4 is connected to a rock lever 5, and said rock lever in turn moves the feed dog back and forth in a well known manner. A bracket 6 is connected to the 90 rock lever 5, and vibrates therewith. Said bracket at its upper end is pivotally connected to a link 7, which is pivotally connected at its other end to the toggle member 3.

A bracket 8 is secured to the bed plate near its lower end, and is attached by means of links and screws hereinafter referred to, at its upper end to the overhanging arm 10 of the machine. The upper toggle mem- 100

ber 11 is provided with a tooth 12, which engages a recess 13 in the lower toggle member 3, and as the lower toggle member is vibrated, the upper toggle member 11 will be similarly vibrated. The upper toggle member is pivoted to a block 14 by a pivot screw 15.

When the screws 18 are loosened, the block 14 may be adjusted vertically, and will 10 carry with it the upper toggle trimming member 11. A screw 19 is threaded into the upper toggle trimming member, and extends through an arc-shaped slot in the block 14. A tension plate 20 is mounted on 15 the shank of the screw 5, and the screw 19 passes through said tension plate, which latter operates to guide the upper toggle trimmer in its vibrations.

The upper toggle trimmer rests directly 20 on the upper surface of the lower trimming member, and said upper toggle trimming member is provided with a blunt surface, which operates to bruise the material passing between the trimming members and 25 thus separate the material. The block 14 is moved downward, so as to bring the trimming members into proper coöperation by means of the wedge 21, which has a threaded stem extending through a bearing 30 or sleeve formed in the upper end of the supporting bracket 8.

The lower face of the wedge 21 bears 35 against the upper edge of the block 14. An adjusting screw 22 is threaded on the shank of the wedge 21, and rests against the bearing supporting the wedge 21. By turning the screw 22 in the proper direction, the wedge 21 may be drawn to the right, as shown in Fig. 3, and will crowd the bearing 40 block 14 downward, thus increasing the pressure between the toggle trimming members. By turning the adjusting screw 22 in the opposite direction, the wedge may be 45 released, and the pressure between the trimming members likewise released.

The parts thus described are constructed substantially as in the Durand patent, except as to the attachment of the bracket 8 to the overhanging arm. The mechanism 50 shown for holding the adjusting screw in adjusted position is not of my invention, but is herein shown as consisting of the following devices:

The shank of the screw has rigidly secured thereon a ratchet wheel 23. A locking pawl 24 is pivoted at 25 to the bracket 8, and has a hooked nose 26 engaging the teeth of the ratchet wheel, and prevents the adjusting nut from turning in a counter-clockwise direction.

The pawl 24 is held in engagement with the ratchet wheel by a spring 27, which is wound about the shank of the pivot screw for the pawl, and engages the tail of the

pawl and presses the opposite end of the 65 pawl against the ratchet wheel. When it is desired to turn the adjusting screw so as to release the pressure between the toggle members, the tail of the pawl may be pressed, the hooked nose thereof thrown out 70 of the ratchet, and the adjusting screw turned, so as to release the wedge.

The bearing or sleeve 28 on the bracket 8, through which the screw stem of the wedge 21 passes, is supported in the ends 75 of two parallel links 29, which at their opposite ends are pivoted by means of screws 30 to the block 31, on the head of the machine.

The outer ends of these links 29 are 80 squared off, as shown, to receive the lower ends of adjusting screws 32, passing through projecting lugs on the block 31. The strain, therefore, on the upper toggle is transmitted 85 to the pivoted links, which are held from displacement by the screws 32, and the springing of the gooseneck is prevented by the web or connection B.

It will be seen, therefore, that the sleeve which is on the bracket 8 is supported by 90 the pivotal links, and when the bracket and upper toggle member are set in the proper position, the screws 32 are forced into position against the links 29, and thus a rigid structure is formed.

As fully described in the Durand patent, the bracket supporting the trimmer is capable of lateral adjustment whereby the trimmer may be properly positioned relative to the stitching mechanism. This is accomplished in a general way by sliding the supporting bracket 2 by an adjustable rod 35. The bearing or sleeve 36 at the upper end of the bracket 8, is capable of slight lateral adjustment in the links 29 to permit 105 of this adjustment of the trimmer relative to the needle.

When the trimmer is adjusted laterally, it is quite essential to provide some means for closing up the space in the work support so as to prevent the trimmed-off portion from passing beneath the work support. The trimmed-off portion of the fabric passes through the slot 37 in the bracket 8.

As clearly shown in Figs. 4 to 9 inclusive, 110 I have provided a work plate slide 38 which is provided with the usual tapered edges and slides in a race or recess extending from the front of the machine toward the stitching point in a direction parallel to the 120 line of feed, and at one side thereof. This work plate slide is cut away as at 39, to allow for the lateral adjustment of the bracket carrying the trimmers. A sliding plate 40 is mounted on the work plate slide, 125 and a spring 41 normally presses said plate against the bracket 8. Said plate is guided in its back and forth movement by the

screws 42 shown in dotted lines in Fig. 5, and in full lines in Fig. 6.

A handle 43 may be provided for moving the slide away from the bracket when it is 5 desired to withdraw the work plate slide. The slots in which the screws 42 are located, serve to limit the movement of the slide 40 through the action of the spring 41. This spring 41 is housed in a depending lug having 10 a recess formed therein for this purpose. A lug is attached to the under face of the slide, and said spring bears against a shoulder carried by the slide 40.

In Figs. 8 and 9 I have shown the slide 15 38 as having a cut away portion, and said cut away portion is covered by a plate 42', which is rigidly attached to the bracket 8 by suitable screws 42. This plate overlaps the work plate slide, and serves to close the 20 opening formed therein, as clearly shown in the drawings.

While I have shown a vertical web or connecting piece B between the gooseneck and the bed, it will be obvious that other 25 means may be employed for strengthening the overhanging arm, and for preventing the upward spring of said arm at the outer end thereof. It will also be obvious that minor changes in the details of construction 30 may be made, without departing from the spirit of the invention, as set forth in the appended claims.

Having thus described my invention, what I claim as new and desire to secure by Letters Patent, is:—

1. A trimming mechanism including a work support, an overhanging arm, a pivoted upper trimming member, adjustable means above the pivot of said trimming 40 member and between said pivot and the overhanging arm whereby the upward thrust of the trimming member is taken up by the overhanging arm.

2. A trimming mechanism including a work support, an overhanging arm, an upper trimming member, a bracket supporting the same, and means located directly above the bracket and between said bracket and the overhanging arm for taking the upward 50 thrust of the trimming member.

3. A trimming mechanism including a work support, an overhanging arm, an upper trimming member, links on the overhanging arm, connections between the links 55 and the bracket, and adjustable means between the links and the overhanging arm for taking the upward thrust of the trimming member.

4. A trimming mechanism including a work support, an overhanging arm, an up-

per trimming member, a support therefor, a sleeve connected with the support, links pivoted on the overhanging arm and embracing the sleeve, and stop screws carried by the overhanging arm and bearing respectively 65 on the free end of the links.

5. A trimming mechanism including a work support, an overhanging arm, an upper trimming member, a support therefor, a sleeve connected with the support, parallel 70 links pivoted at one end to the overhanging frame, and at their free ends supporting the sleeve, and stop screws attached to the overhanging arm and bearing on the free ends of the links.

6. A trimming mechanism including a standard, a bed plate and an overhanging arm, an upper trimming member, adjustable means located directly above the upper trimming member and between said upper trimming member and the overhanging arm, whereby the upward thrust of the trimming member is taken up by the overhanging arm, and a strengthening web or connecting piece between the overhanging arm and 80 the bed plate.

7. A sewing machine including a bed plate, a standard, an overhanging arm, a trimming device having two members arranged in a vertical plane, one directly above 90 the other, means located directly above the trimming members and between the trimming members and the overhanging arm for taking up the upward thrust of the trimming members, and a strengthening piece 95 extending substantially parallel with the trimming devices and its members for connecting the bed plate and said overhanging arm.

8. In a sewing machine including a bed 100 plate, a work support, a standard, and an overhanging arm, a trimming device including trimming members and a frame to which said members are attached, means whereby said trimming device can be adjusted toward and away from said standard, said work support being provided with openings for said trimming device and for access to the working parts of said sewing machine, one of said openings having a closing device 105 provided with an adjustable part to compensate for the lateral movement of said trimming device.

In testimony whereof, I affix my signature, in the presence of two witnesses.

LANSING ONDERDONK.
